DRILL PRESS HEAD

Herbert E. Tautz, Milwaukee, Wis., assignor to
Delta Manufacturing Company, Milwaukee,
Wis.

Application December 8, 1933, Serial No. 701,515

10 Claims. (Cl. 248—16)

The invention relates to a head for use on a drill press or similar tool having a rotary spindle.

Specifically, it relates to a head having there-in a bearing for supporting a spindle and means 5 cooperating with said head for supporting a motor for driving said spindle, both the spindle and the motor shaft each preferably being provided either with several separate pulleys or with cone pulleys.

10 More specifically, the invention relates to means for shifting the motor with respect to the head, whereby the motor may be moved toward and from the spindle, mounted in the head, and may also be raised and lowered bodily to vary the 15 alinement of the respective pulleys, so that any pulley or any step of a cone pulley on either the motor shaft or the drill spindle may be correctly and quickly alined with any desired pulley or step on the other shaft and further means whereby 20 the spacing of the said two shafts may quickly be altered to correspond with the length of the belt being used.

Still more specifically, the invention relates to 25 means permitting rapid adjustment of the motor toward and from the drill spindle and further means having definite stop positions for quickly shifting the motor in a direction parallel to the axis of the drill spindle in definite steps and automatically locking the same when such shifting 30 has been accomplished.

By the combination of these two adjustments it is obvious that the selected motor pulley or 35 cone step may be quickly alined with the selected pulley or step on the drill spindle and locked in such position of alinement and there-upon the motor may be shifted bodily to properly tighten the belt and also locked in such position, thus easily, speedily and automatically accom- 40 plishing an operation which would otherwise require considerable time and effort, if performed manually and without mechanical assistance.

Other objects and advantages of the invention will in part be specifically pointed out in the following specification and drawings and will in part 45 be obvious from the structure disclosed.

For a clearer understanding of the invention, attention is directed to the following specifica-tion in connection with the accompanying drawings wherein:

50 Fig. 1 is a side elevation of a drill press head combined with a motor, and embodying the invention.

Fig. 2 is a plan view of the structure disclosed 55 in Fig. 1.

Fig. 3 is a sectional view on the plane indicated by the line 3—3 of Fig. 1, looking in the direction of the arrows and showing certain details of the motor mounting.

Fig. 4 is an elevation of the base upon which 5 the motor is mounted, as seen from the side opposite to that disclosed in Fig. 3.

Fig. 5 is a horizontal section of the structure illustrated in Fig. 4, said section being made on the planes indicated by the broken line 5—5 of 10 Fig. 4.

Fig. 6 is an elevation of a modified motor mounting base which may be substituted for that illustrated in detail in Figs. 3, 4 and 5, certain parts being shown in section.

Fig. 7 is a horizontal section of the structure illustrated in Fig. 6, said section being made on the planes indicated by the broken line 7—7 of 15 Fig. 6.

Fig. 8 is a fragmentary elevation showing a 20 modified form of operating mechanism which may be employed in place of that provided in Figs. 6 and 7.

Fig. 9 is an elevation of a still further modified motor mounting base which may be substituted 25 for that illustrated in detail in Figs. 3, 4 and 5.

Fig. 10 is an elevation of another modified motor mounting base which may be substituted for that illustrated in detail in Figs. 3, 4, and 5.

Fig. 11 is a detail cross section on the plane in- 30 dicated by the line 11—11 of Fig. 10 showing the locking pin structure employed in said figure.

Fig. 12 is a fragmentary diagrammatic eleva-tion of another modification of motor mounting base wherein a screw is used, instead of the gears 35 or levers employed in the preceding forms, for shifting the motor vertically through a pre-determined distance.

Fig. 13 is a corresponding fragmentary dia- 40 grammatic elevation of a still further modifica-tion also using a screw for shifting the motor.

Fig. 14 is a fragmentary elevation of the struc-ture illustrated in Fig. 13, as seen from the right, 45 showing certain details of the motor mounting base on a larger scale and certain rods in cross section, and

Fig. 15 is a sectional detail view of a portion of the structure illustrated in Fig. 14, on the plane indicated by the line 15—15.

In the various figures similar parts are design- 50 nated by the same reference characters.

Referring first to Figs. 1 and 2, there is illus-trated a support 1, here shown as tubular, which may be mounted in any suitable way and which serves to slidably support the drill head 2. The 55

drill head is preferably bored as shown at 3 to fit slidably upon the member 1 and a slot or the like 4 is provided leading into the bore 3 to furnish a certain amount of resilience or "give" to the said bore 3, whereby it becomes possible to secure the drill head 2 firmly to the support 1 at any desired position of adjustment, by suitably tightening the bolt 5, which passes through the drill head adjacent the bore 3 and has a nut 6 at its other end, suitable washers 7 being interposed, if desired.

The head 2 is provided also with an enlarged portion 8 which is suitably bored to receive the quill 9 through which passes the drill spindle 11. The head is also preferably provided with a flared or bell-shaped portion 10, serving to guard and conceal the pulleys 12 and 13 which are suitably keyed to the spindle 11 by means of the keyways 14 in said spindle, cooperating with keys 15 moving with the pulleys as best shown in Fig. 2.

The pulleys 12 and 13 may, of course, be separate pulleys cooperating with the spindle or may be the two steps of a cone pulley, this being a matter of no importance as far as the present invention is concerned. The usual operating lever 16 may be provided for locking the quill 9 in the head at any desired position of adjustment and the quill preferably has a scale 17 which may cooperate with a pointer carried by a rod 18 to indicate the position of the said quill. Means comprising a shaft 19 for moving the quill 9 may also be provided in the customary manner.

The parts thus far described form no part of the present invention and are disclosed therein merely to assist in the understanding of the invention which cooperates therewith.

It will be noted that the motor 20 is preferably of the vertical shaft type, that is, a motor built with bearings and other parts of the proper kind to operate satisfactorily when the shaft is in a vertical position. By providing a motor of this type it becomes possible to belt the same directly to the drill spindle without requiring any twisted belts or idler pulleys cooperating therewith and the arrangement is materially simplified. The motor may have a switch 32 mounted thereon for convenience.

The motor has a shaft 21 carrying a cone pulley 22, having any desired number of steps, as 23, 24 and 25 in the specific instance illustrated. This cone pulley is suitably secured to the shaft 21 and it is, of course, obvious that a series of individual pulleys arranged adjacent one another will accomplish the same purpose, if preferred.

A belt 26 is provided to connect the pulleys 23, 24 and 25 with the pulleys 12 and 13, on the spindle 11, and in order to make it possible to employ a single belt for this purpose it is obvious that means must be provided for shifting the motor shaft 21 with respect to the drill spindle 11, because the various pulleys are of different diameters and would, of course, require either belts of different lengths or a shifting of the motor as a whole, if a single belt is to be used.

This shifting of the motor to vary the distance between its shaft and the spindle of the drill may be accomplished in a very simple manner by providing a suitable rod or rods 27, passing through bores in the bosses or lugs 28 formed in the drill head 2, two such rods being shown in the form illustrated. Each of the lugs 28 preferably has a boss or lug 29 formed thereon, and suitably threaded to receive a clamping screw 30. The motor 20 is carried by said rod or rods 27 and it is obvious that by slightly loosening the clamping screws

30 it becomes possible to shift the rod or rods 27 in the bores in lugs 28 to secure the proper tension of the belt 26, whereupon the said rod or rods 27 may be again secured by use of the clamping means 30.

If the pulley intended to be driven by the motor were always properly aligned in a horizontal direction with the desired pulley on the motor shaft, there would be no further adjustment necessary to provide proper operation of the drill 10 spindle from the motor shaft. However, it may be that the desired motor and drill pulleys are not in proper horizontal alignment with one another, in which case, of course, it becomes necessary to shift one or the other of them vertically 15 with respect to the remaining one. Obviously either of the pulleys could be so shifted, but for reasons of simplicity in operation and ease of manufacture it is simpler to shift the motor vertically, leaving the adjustment of the drill head 20 undisturbed. This may be accomplished by the means indicated generally at 31 in Figs. 1 and 2 and shown in greater detail in Figs. 3, 4 and 5.

The mechanism which, as stated, is indicated as a whole by reference character 31 in Figs. 1 25 and 2, comprising a plate 33, which may be secured to the rod or rods 27 in any desired way, for example by nuts 35 engaged on the reduced threaded ends 36 of the rods 27, as best shown in Figs. 4 and 5. It is thus obvious that the plate or 30 sub-base 33, together with the rod or rods 27, forms a rigid structure, which forms a relatively stationary portion with respect to which the motor and its motor base support may be adjusted vertically, that is, in a direction parallel to the shaft 35 11 of the drill.

In order to provide for such adjustment of the motor, a further plate 34 may be provided which is held flat against the plate 33 by means of brackets 37 secured to the 40 plate 34 in any suitable manner, for example, by screws 38. Each bracket 37 has a projecting portion 39 which, together with the plate 34, forms a suitable channel to receive an outer edge of the plate 33. Suitable openings 40 45 of elongated form may be provided in the plate 34 in order to receive the nuts 35 and reduced ends 36 of the rods 27, but permit relative motion in the direction of sliding in the said brackets. Each of the brackets 37 is also preferably slotted, 50 as shown at 41, and similar slots 42, alined with said slots 41 of the brackets may be formed in the plate 34, as best shown in Figs. 3 and 4.

Through these slots 41 and 42 may pass bolts 43 adapted to pass also through the customary 55 bolt holes provided in the base of the electric motor 20, whereby said motor may be rigidly secured to the plate 34 by tightening the nut 44 on each of the bolts 43, lock washers 45 being preferably interposed in the customary way to prevent loosening of the said nuts 44. The bolts 43 may advantageously be of the type commonly known as carriage bolts, which have squared portions just beneath the head, as shown at 46, which will engage the sides of the slots 41 and 42, where- 65 by each bolt as a whole will be prevented from turning with respect to the base 34 when the nut 44 is being tightened or loosened. The carriage bolt has a further advantage in that the head 47 thereof occupies very little room and does not 70 get in the way of other parts of the mechanism.

It is obvious that the structure thus far described provides a stationary plate 33 and a further plate 34 which slides along said plate 33, the motor being clamped to the movable plate 75

34 by means of the bolts and thus partaking of the sliding motion thus provided. It is also obvious that the motor 20 may be clamped in any desired position with respect to the plate 34 by 5 suitably shifting the bolts 43 in the slots 41 and 42, in order to bring one of the pulleys 23, 24 and 25, attached to the shaft 21 of said motor, into initial horizontal alinement with one of the pulleys 12 or 13 arranged on the drill spindle 11. 10 This initial adjustment is useful in a way which will be explained in greater detail in discussing the operation of the device.

In order to adjust the plate 34 as a whole up and down with respect to the plate 33, a mechanism is provided which consists in the form shown in Figs. 1 to 5 of a rack and pinion, the rack comprising a series of teeth indicated at 147 and cut in a vertical edge of the plate 33 and the pinion consisting of a series of corresponding 20 teeth meshing with the teeth 147 and provided in a member 48 which is pivoted about a bolt or the like 49 secured to the plate 34 by means of a nut 50, a washer 51 being preferably interposed between the nut and the member 48.

25 A spacing bushing 52 as well as a bearing washer 53 may also be located around the said bolt 49, as best shown in Fig. 5. The head of the bolt 49 is preferably of the type known as a flat head, as shown at 54 and is countersunk so as 30 to be flush with the outer surface of the plate 34 so that said head 54 will not obstruct any of the other parts of the mechanism. The member 48 is suitably bored to receive the bushing 52 whereby said bushing 52 constitutes a bearing or pivot 35 about which member 48 may be turned and the washer 53 serves as an abutment and reinforcement against which one end of the bushing 52 bears when the nut 50 is tightened on the bolt 49.

The member 48 is, of course, suitably counter-bored to receive the washer 53 and the length of the bushing 52 is made sufficient to prevent the member 48 from binding upon the same when the nut 50 is tightened, whereby the bolt 49 and its cooperating bushings and washers may be 45 adequately and securely tightened without interfering with the free operation of the member 48 about its pivot.

It is clear that by reason of the meshing of the 50 pinion teeth 55 of the member 48 with the rack teeth 147 on the member 33, the plate 34 will be caused to move with respect to the plate 33, whenever the member 48 is rotated about its pivot. In order to provide definite degrees of movement of the plate 34, the said plate 34 may be provided 55 with a notched segment 56, best shown in Figs. 3 and 4, said segment being provided with any desired number of notches, three being illustrated in the present case, and designated as 57, 58 and 59, respectively.

60 A cooperating stop, made preferably in the form of a slidable pin, 60, having a suitable head or handle 61, may be supported by an arm 61 forming a part of the member 48, preferably by providing aligned bores in lugs 62 and 63 formed 65 as a part of said arm 61 and adapted to receive said pin 60 in proper position to aline it substantially with the central plane of the plate 34, as best shown in Fig. 5.

60 A spring 64 may surround the pin 60 and may be retained at one end against the inner surface of the lug 63 and at its other end may bear against the washer 65 secured to the pin 60 by means of a cross pin 66, so that the spring 64 will always urge the pin 60 toward the center of rotation of the member 48. By reason of this arrangement

of the parts it is obvious that the inner end of the pin 60 will always tend to snap into any one of the notches 57, 58 or 59, with which it may come into alinement, thus preventing any further relative rotation of the member 48 with respect to the plate 34 one such locking engagement of the pin 60 has taken place in any of said notches.

By properly spacing these notches 57, 58 and 59 to provide the desired intervals of vertical movement of the plate 34, it is obvious that said plate 34 may be rapidly and automatically adjusted into desired positions of vertical adjustment, the motor 20 being raised or lowered as a whole, together with the plate or base 34 to which it is secured. These vertical intervals of movement corresponding to the distances between the notches 57, 58 and 59 are preferably chosen to be equal to the vertical distances between the central planes of the pulleys 23, 24 and 25 and are 20 preferably uniform with one another, although this is not always indispensable or necessary.

Referring now to the modified motor base, shown in Figs. 6 and 7, it will be noted that the plate 33, which in the preceding form carries the 25 rack teeth 147, is now provided instead with a series of notches in one edge, said notches being designated respectively as 68, 69 and 70, and being three in number in the form illustrated, this number corresponding to the number of steps 30 or pulleys used on the motor and being spaced apart by intervals corresponding to the thicknesses of said respective steps or pulleys.

A pin 71 having a suitable handle or head 72 is adapted to cooperate with the notches in the edge of the plate 33, for example in Fig. 6, the end 73 of the pin 71 is shown as engaged in the notch 69. The pin 71 may be actuated by means of a spring 64 bearing against a washer 65 and secured by a pin 66, these parts being identical 40 in construction and operation with those of the preceding form. The pin 71 may be slidably mounted in a bore 74 of a lug or extension 75 formed on or secured to the plate 34, as clearly shown in Figs. 6 and 7. The remaining structure 45 shown in Figs. 6 and 7 is identical with the structure denoted by similar reference characters in the preceding figures.

It will be noted that the upper and lower notches 68 and 70 differ from the central notch 69 in that each of said outer notches has one edge longer than the other, in other words, the outer portion of each of these notches has a certain degree of overhang. The pin 71 is so arranged that the end 73 thereof may be drawn to the left 50 from the position shown in Figs. 6 and 7 to an extent sufficient to clear the projections 76 and 77 formed between the notches 68, 69 and 70, but not sufficiently far to clear the overhanging portions 78 and 79, so that even when the pin 71 is drawn to the left as far as possible, the end 73 will nevertheless catch on either 78 or 79, thus limiting the total range of movement of plate 34 with respect to plate 33 for a purpose which will 55 be explained when the operation of this form of device is discussed.

The extent of sliding movement of the pin 71 in the bore 74 may be thus limited by reason of the abutment of the washer 65 against the inner end 80 of the portion 75, or in any other suitable 60 way, to secure the desired result.

The form of device shown in Fig. 8 is identical in all respects with that disclosed in Figs. 6 and 7 with the exception that in the Fig. 8 form a lever 81 is provided, which may be pivoted to the mem- 75

- ber 75, as indicated at 82, the lever 81 being bent at one end to provide a forked or apertured portion 83 loosely engaging about the pin 71 and abutting against the head 72 of the said pin.
- 5 These parts are so arranged that upon forcing the long arm of the lever 81 toward the member 75, the short arm 83 of the said lever will withdraw the pin 71 from engagement with the notches 68, 69 or 70 of the plate 33.
- 10 A further modification for accomplishing the desired results is disclosed in Fig. 9. In this figure the plate 33 may be provided with a slot 84 extending partly within the plate proper and formed partly in a tab or extension 85, extending preferably at right angles to the edge of said plate 33. This slot 84 accommodates a short pin or stud 86 secured to one arm of a lever or operating handle 87, which is substantially identical in structure and function with the portion 61
- 15 of the member 48 illustrated in Figs. 2 to 5, that is, this member is pivoted about the bolt 49 having the nut 50 located thereon and has a slidable pin 60 with a head 67 and a surrounding spring 64, said sliding pin 60 cooperating with notches 57, 58 and 59 in the segment 56, precisely as in the Figs. 2 to 5 form, but differs from said form in that the short end 88 of the lever 87 terminates merely in the pin 86, which is engaged slidably in the slot 84, instead of having a set of pinion teeth cut therein.
- 20
- 25
- 30
- 35
- 40
- 45
- 50

This slot 84 is made of suitable length to accommodate the pin or stud 86 when said pin moves to the right or left, due to rotation of the lever 87 about its pivot at 49 and the parts are so proportioned that when the end of the latch pin 60 engages in the respective notches 57, 58 and 59 of the segment 56, said pin 86 will raise or lower the plate 34 by the desired amounts corresponding to the thickness of the pulleys or steps of the cone pulleys on the motor shaft. The pin 60 will, of course, lockingly engage or latch in any one of these notches exactly as in the form shown in Figs. 1 to 5.

A still further modification is disclosed in Figs. 10 and 11. Here again the plate 33 is made to be very similar to the same plate as shown in Fig. 9, that is, it has a projecting lug 88 at one edge thereof and the plate 34 is provided with a series of holes 89, 90 and 91, which are spaced apart a distance corresponding to the desired spacing of the pulleys or steps.

A pin 92 carried by a spring 93 secured at 94 to the plate 33 and having a head 95 for convenience in manipulating it, is arranged to pass through a suitable aperture 96 in the plate 33 and engage in any selected one of the openings 89, 90 or 91, so that the plate 34 may be adjusted up or down to the proper extent, by merely pulling the pin 92 out of engagement with plate 34 against the effort of the spring 93, whereupon the plate 34, together with the motor carried thereby, may be manually lifted or lowered until the pin 92 automatically snaps into the desired one of the holes.

65 The extension or lug 88 will serve also as a safety stop and prevent the plate 34, together with the motor carried thereby, from accidentally falling, by engaging against the upper bracket member 31, in case of such accident. In other respects the remaining parts of Figs. 9 and 10 are identical with those of the preceding figures.

70 Referring now to Fig. 12 it will be seen that the motor 20 is carried by a plate or base 134 corresponding in function to the plate 34 of the preceding figures, the motor being connected to said

75 plate 134 by means of the bolts 43 and nuts 44 as in said previous forms and being capable of preliminary adjustment in slots in said plate 134 exactly like the slots 42 in the plate 34.

The plate 134 differs, however, from the plate 34 in having a flange or lug 97 arranged at or near its upper end and extending substantially at right angles to the plate 134. This lug 97 is provided with a screw-threaded bore 98 receiving a screw 99 provided with a handle or other operating means 100 and with an indicator 101. The pitch of the thread of the said screw 99 is preferably made equal to the center-to-center distance of the pulleys or the cone pulley steps on the shaft 21.

The indicator 101 may be a pointer or any other desired element capable of giving a point of reference when the operating means 100 is rotated to turn the screw 99. The plate 133 also may be provided with a lug or flange 102 extending substantially at right angles thereto and adapted to serve as an abutment for the end 103 of the said screw 99. The plate 134 slides freely vertically with respect to the plate 133 by means of the brackets 37, which are identical with those in the preceding forms.

The form described in Figs. 13 to 15 inclusive is similar in general to the Fig. 12 form, except that it is more elaborate and more convenient, and is positive in operation. A plate 233 corresponding to the plate 33, of Figs. 1-5, and a co-operating plate 234 corresponding to the plate 34, are provided, the plate 234 having a lug or projection 104 extending preferably at right angles at or near its upper end, as shown, and cooperating with the upper end 105 of a screw 106, which passes through a lug or flange 107 attached to or forming a part of the plate 233 and threaded at 108 to receive said screw 106, said screw having also a preferably unthreaded extension or shaft 109 which passes through another lug or projection 110, which may be formed on or secured to the lower end of the plate 233 and have a bore 111 to afford a bearing for the shaft portion 109 of the screw. The pitch of the thread of the screw 106 is preferably made equal to the center-to-center distance of the pulleys or cone pulley steps on the shaft 21. The screw shaft 109 is preferably provided with an operating member 112, here shown as a star wheel.

The shaft 109 of the screw is provided with a slot or groove 113 cooperating with a pin or latch 114, which is actuated by means of the spring 115, which urges the pin 114 to the left, in the position shown in Figs. 13 and 15. A head 116 may be provided on said pin 114 for ease of manipulating the same in order to cause the end 117 of the pin to be withdrawn from the groove 113 and a pin 118 and washer 119 may be provided to retain said spring 115 engaged on the pin 114.

60 This pin 114 may conveniently pass through a suitable bore 120 in a lug 121 which may be formed on the lug 110.

The operation of the various devices above described is as follows:

65 Referring first to the form illustrated in Figs. 1 to 5 inclusive, it will be noted that in Fig. 1 the belt 26 links the lower step 13 of the cone pulley, on the spindle 11 of the drill, with the middle step 24 of the cone pulley 22 on the motor shaft 21 and this belt is properly tightened so that the device is in operative condition.

70 Let it now be assumed that it is desired to decrease the speed of the drill spindle to its lowest

possible speed. This can evidently be done by disengaging the belt 26 from the step 24 and engaging it in the step 25, while leaving it engaged with the step 13 of the other cone pulley. However, in Fig. 1 the step 24 is in horizontal alignment with the step 13, whereas the step 25 is not in such alignment with the step 13, and, moreover, as adjusted in Fig. 1, the belt is of just the proper length to correctly connect the steps 24 and 13 and it would be too long to connect the steps 25 and 13.

Therefore, in adjusting the apparatus to cause the belt 26 to link together the steps 25 and 13 properly, the first operation is to raise the motor 20, as a whole, by means of the handle 67, which is done by first pulling the pin 60 out of engagement with the notch 58 (Fig. 4) and then raising the head or handle 67 of the said pin 60 until the inner end of the pin 60 aligns with the notch 57. The spring 64 will, of course, cause the inner end of the pin to spring into said notch 57 and thereby secure the element 61 in a definite position with respect to the plate 34.

Inasmuch as the plate 33, which is secured to the rods 27, is held at a definite elevation by reason of the fact that said rods 27 are held at a definite vertical position with respect to the head 2 of the drill, this operation of the member 61 will cause the plate 34 to rise a definite distance, due to the engagement of the pinion teeth 55 of the member 48 with the teeth of the rack 147.

This distance is made to be equal to the distance from center-to-center of the steps of the cone pulleys, in the original designing of the apparatus, so that the mere act of raising the said lever 61 into proper position to cause the pin 60 to engage in notch 57 will automatically elevate the entire motor and the cone pulley carried thereby accurately to a distance equal to the said center-distances of the various steps or pulleys, thus properly alining the step 25 with the step 13 in a horizontal plane.

The motor when so raised to adjust the step 25 into horizontal alignment with the step 13 will be in the position indicated in the dashed lines in Fig. 3, which show also the positions assumed by the supporting plate 34 and the mechanism carried thereby, including the lever 61 and its cooperating parts. However, inasmuch as the belt 26 would now be too loose, it is necessary to move the motor shaft 21 to a greater spacing from the drill spindle 11 and this is accomplished by moving the entire motor toward the left from the position indicated in Fig. 1, namely, by loosening the thumb screws 30 and sliding the rod or rods 27 to the left in the bosses or lugs 28 until the belt 26 is properly tensioned, whereupon the rods 27 and the motor carried thereby may, of course, again be tightened to hold the motor in such adjusted position.

A similar operation of the member 61 in the opposite direction, namely, downward from the position shown in Figs. 1, 3 and 4 will, of course, result in horizontally alining the step 23 with the step 13 and in this case the belt 26 would be too short, so that, of course, the rods 27 would be moved to the right from the positions shown in Figs. 1 and 2 and then clamped at a suitable position of adjustment by using the said thumb screws 30.

It is, therefore, obvious that any one of the steps on the cone pulley 22 may thus be alined with either step of the cone pulley on the spindle 11 and it will, of course, also be understood that

while in the present case the cone pulley on the motor shaft has been shown as having three steps and that on the drill spindle as having two steps this is merely an arbitrary matter and the actual number of steps in either or both pulleys 5 is entirely a matter of design or appropriateness to existing conditions, so that any desired number of steps may be employed in either pulley, and even a single-step pulley might be used on either shaft, if preferred for any reason, without 10 sacrificing many of the advantages of the invention.

Briefly expressed, this invention relates to means for bringing the motor shaft pulley quickly and accurately into the proper horizontal alignment with the drill spindle pulley and for also rapidly adjusting the belt to its proper tension and it is clear that many other ways of doing this will obviously also be included under the same 20 inventive idea.

In order to bring the motor initially into the position shown in Fig. 1, wherein one step such as 24 is alined horizontally with a step of the other pulley, such as 13, use may, of course, be made of the customary clamping bolts 43 and nuts 44 cooperating with the slots 41 and 42 (Fig. 3) so that the motor may be initially adjusted manually to bring the pulleys into such proper horizontal alinement and thereupon the motor may be permanently secured to the plate 30 34 by tightening the nuts 44, inasmuch as any later adjustment of the motor in a vertical direction, when in use, is done automatically by the mechanism just described and operated by means of the handle 67. 35

While the form of the device described and illustrated in Figs. 1 to 5 inclusive is the preferred form and provides for very easy manipulation of the motor by reason of the leverage provided by the arm 61, it is clear that owing to the greater 40 expense of manufacture of this form of the device it may in some cases be desirable to provide a simpler and cheaper mechanism for accomplishing similar results.

This may be done, for example, by the form 45 of device illustrated in Figs. 6 and 7. Here again the plate 33, which is supported by the rods 27, serves to support the plate 34 upon which the motor is mounted, as in the form just described, but instead of the pivoted lever 61, a lug 75 housing the pin 71 with its handle 72, is substituted, and this pin 71 may be moved out of engagement with the notch 69 by pulling out the handle 72 just as in the prior described form. 50

However, inasmuch as no rack and pinion is 55 provided in this form, the motor is raised or lowered manually by raising or lowering the handle 75 a sufficient distance to cause the inner end 73 of the pin 71 to engage in the selected one of the notches 68, 69 and 70, these notches being spaced apart the correct distance to correspond to the center-to-center distances of the various steps of the cone pulleys. 60

It is clear that in this form of device, if no 65 means were provided to prevent it, it might be possible through carelessness or accident to allow the entire motor together with the plate 34 to drop off the plate 33, at least to the extent permitted by the openings 40 in the plate 34. In 70 order, however, to prevent such accidental undesired dropping of the plate 34 the shoulder 79 is caused to extend further to the left than the shoulders 76 and 77 and inasmuch as the leftward motion of the pin 71 is limited to an ex. 75

tent only slightly more than sufficient to clear the shoulders 76 and 77, it is obvious that, in case of an accidental dropping, the end 73 of the pin 71 would catch on the shoulder 79 and thus prevent the motor from falling to more than the intended and necessary distance. Similarly the shoulder 78 which also extends to the left of the shoulders 76 and 77 will automatically prevent the plate 34 from being raised more than the necessary amount, so that this portion of the adjustment becomes automatic and prevents any accidental derangement of the device.

The operation of the Fig. 8 form is substantially the same as that of the form shown in Figs. 6 and 7, the only additional feature being the provision of the lever 81. It is clear that upon grasping the handle 75 in the hand and at the same time including the long arm of the lever 81 in the grasp of the operator, upon depressing said lever the short arm thereof will draw the pin 71 to the left a distance sufficient to disengage the inner end 73 from the notches, whereupon the plate 34 may be moved up or down, as in the other forms, and will again automatically be locked, when pressure upon the lever 81 is discontinued, when aligned with one of the notches.

The form illustrated in Fig. 9 is similar, to a certain extent, to that shown in Figs. 1 to 5, in that a pivoted operating lever is provided, and it has the same advantage of ease of operation due to the leverage thus provided. However, this form of device may, in certain cases, offer advantages over the Figs. 1 to 5 form, because it is somewhat cheaper to construct in that it substitutes a pin and slot mechanical movement for the rack and pinion.

In other respects, however, the operation of this form is identical with that of the Figs. 1 to 5 form and in fact it may be considered merely as having a specialized form of rack and pinion, the rack having only a single tooth space, namely, the slot 84 may be considered as forming a tooth space between two rack teeth and the pin 86 may be considered as a single tooth of the pinion. With this understanding of the device it is clear that the Fig. 9 form is merely a special case of the Figs. 1 to 5 form, wherein the gearing is very much simplified by removing all unnecessary teeth from both the rack and the pinion.

The pin 60 will, of course, cooperate with the notches 57, 58 and 59 in exactly the same way as in the Figs. 1 to 5 form and the relative dimensions are made such that shifting said pin from one of said notches to the next will cause the plate 34 to be raised or lowered to an extent exactly equal to the center-to-center distances of the pulley steps, just as in the Figs. 1 to 5 form.

The form shown in Figs. 10 and 11 is the simplest of all and may be used where extreme cheapness is a determining factor. The operation of this form consists in manually raising or lowering the motor, together with its supporting plate 34, after the pin 92 has been withdrawn from the plate 34 by pulling it out by means of its head 95.

The holes 89, 90 and 91 are, of course, spaced apart distances equal to the center-to-center distances between the steps of the cone pulleys, so that when the pin 92 springs into any one of said holes the motor will be latched in its proper position to cause certain of the steps to be aligned with one another in a horizontal direction.

The lug 88 in this form will serve to limit the sliding movement of the plate 34 to the necessary distances, because said lug will abut against one

or the other of the two left hand brackets 37 when the plate is raised or lowered to its extreme positions. It would even be possible, of course, in the form shown in Figs. 10 and 11 to eliminate entirely the upper hole 89, because the lug 88 would, nevertheless, determine the proper lower position of the plate 34 by abutting against the upper plate 37, but it is deemed preferable, nevertheless, to provide the hole 89 in order to furnish a positive locking of the plate 34 against upward movement.

The operation of the forms above described depends on gears or levers or upon mere lifting and lowering of the motor manually. The operation of the forms disclosed in Figs. 12 to 15, however, depends upon screws instead of such gears, levers, etc.

Referring first to Fig. 12 it will be noted that the operation of this form is extremely simple and depends merely upon raising the motor 20 together with its mounting plate or base by turning the screw 99 by means of the operating means 100. As stated, the pitch of said screw is preferably made equal to the center-to-center distance of the pulleys or the steps of the cone pulley on the shaft 21 so that rotation of the screw 99 through one complete revolution will cause the plate 134 to be raised or lowered a corresponding distance with respect to the plate 133.

The raising is, of course, positive and is due to the contact between the end 103 of said screw and the upper surface of the lug 102, but the descent of the motor, together with its plate 134, is produced solely by the weight of said parts, which slide freely by reason of the grooves of the brackets 37, in engagement with the plate 133.

The extent of rotation of the screw 99 may be readily noted by means of the pointer or other indicator 101, which clearly shows when each revolution is completed by again lining-up in a definite direction of reference, which may, of course, be chosen arbitrarily, that is, it may point toward the shaft 21, opposite to said shaft, to the right, or to the left, etc., as preferred. It is clear, however, that this affords a ready means for adjusting the motor vertically to the desired extent and dropage of the motor and its plate 134, due to excessive rotation of said screw 99, is, of course, made impossible by the fact that the lug 97 would engage against the upper end of the plate 133 and prevent further downward movement of the plate 134 and the motor carried thereby.

The form described in Figs. 13 to 15 is in some respects similar to the Fig. 12 form, but has added features of convenience and utility. It is obvious that by rotating the screw 106 by means of its star wheel 112 or other operating device, the entire plate 234, together with the motor carried thereby, may be raised by reason of the engagement of the end 105 of said screw against the lower surface of the lug 104.

Here again the rotation of the screw 106 through one complete revolution will cause the motor to be raised or lowered the requisite distance to correspond to the center-to-center distance of the various pulleys or the steps of the cone pulley and an added convenience is provided by means of the positive latching accomplished by the pin 114 in cooperation with the groove or slot 113.

It is obvious that the end 117 of the pin 116 will snap into the groove 113 whenever the pin is aligned with the said groove and inasmuch as one turn of the screw corresponds to the desired rise or descent of the motor, it is clear that it will be

necessary merely to disengage the pin 114 from the slot 113 and thereupon again release the pin after slightly turning the screw 106, whereupon said pin will again engage within the groove 113 upon the completion of one turn of said screw, thus again latching the said screw against further rotation and holding the pulleys in proper alignment.

This form also provides a positive lifting of the motor base plate 234 and the motor carried thereby, and the descent, as in the Fig. 12 form, is accomplished solely by the weight of the parts. The downward location of the screw 106 is, however, a further added convenience and improvement over the Fig. 12 form, as the screw is less likely to be in the way in this position.

As already mentioned above, it will, of course, be understood that the number of pulleys on the various shafts, that is, the motor shaft or the 20 drill spindle, is purely arbitrary and either shaft may, in certain cases, have only a single pulley, while the other has a greater number. In order to provide for this in the claims, the term "number" is used therein in its broader mathematical 25 sense, to mean any positive integral number, inclusive of unity, so that the term "number" when used in the claims is, therefore, equivalent to the expression "one or more", but does not necessarily mean "a plurality". It will likewise be understood 30 that the term "pulley" is for convenience used to designate either an independent pulley or merely one of the steps of a cone pulley, where such term appears in the claims.

Having described a preferred embodiment of the invention and various modifications thereof, it will be understood that many changes, additions, omissions, etc., can be made therein without departing from the inventive idea, and, therefore, said invention is not to be considered as 40 limited to the specific embodiments illustrated, but only as specified in the following claims.

I claim:

1. In a drive mechanism, in which there are substantially parallel drive and driven shafts, each having a number of spaced pulleys thereon, a motor support whereby a motor embodying such drive shaft may be supported and adjusted independently in two directions at right angles to one another, and comprising an element supported to move in a direction transverse to the axis of rotation of the motor, a sub-base carried by said element, a motor base support carried by said sub-base, means for shifting the motor base support in a direction parallel to the axis of rotation of the motor, and means for predetermining the extent of such adjustment to be equal to the spacing of said pulleys and for latching the adjusting device automatically when such predetermined adjustment has been made.

2. In a drive mechanism, in which there are substantially parallel drive and driven shafts, each having a number of spaced pulleys thereon, a motor support whereby a motor embodying such drive shaft may be supported and adjusted independently in two directions at right angles to one another, and comprising an element supported to move in a direction transverse to the axis of rotation of the motor, a sub-base carried by said element, a motor base support carried by said sub-base, means for shifting the motor base support in a direction parallel to the axis of rotation of the motor, and means for predetermining a number of steps of such adjustment to be equal to the 75 respective spacings of the pulleys and for latching

the adjusting device automatically when any such predetermined step has been reached.

3. In a drive mechanism, in which there are substantially parallel drive and driven shafts, each having a number of spaced pulleys thereon, a motor support whereby a motor embodying such drive shaft may be supported and adjusted independently in two directions at right angles to one another and comprising an element supported to move in a direction transverse to the axis of rotation of the motor, means for securing said element in its adjusted position, a sub-base carried by said element and extending in a direction substantially at right angles to the said direction of movement, a motor base support carried by said sub-base, and means for adjusting said motor base support in a direction parallel to the axis of rotation of the motor, in a number of predetermined steps each equal to the spacings of the respective pulleys along said sub-base and for locking it in its adjusted position.

4. A motor support whereby a motor may be supported and adjusted independently in two directions at right angles to one another and comprising an element supported to move in a direction transverse to the axis of rotation of the motor, means for securing said element in its adjusted position, a sub-base carried by said element and extending in a direction substantially at right angles to the said direction of movement, a motor base support carried by said sub-base, means comprising a rack and pinion for adjusting said motor base support in a direction parallel to the axis of rotation of the motor, with respect to said sub-base and means for locking it automatically at any one of a number of predetermined positions.

5. In a drive mechanism, in which there are substantially parallel drive and driven shafts, each having a number of spaced pulleys thereon, a motor support whereby a motor embodying such drive shaft may be supported and adjusted independently in two directions at right angles to one another, and comprising an element supported to move in a direction transverse to the axis of rotation of the motor, a sub-base carried by said element, a motor base support carried by said sub-base, a lever for shifting the motor base support in a direction parallel to the axis of rotation of the motor, and means comprising a number of stops and a latch cooperating therewith for predetermining a number of steps of such adjustment each equal to the spacings of the respective pulleys and for latching the lever automatically when any such predetermined step has been reached.

6. A motor support whereby a motor may be supported and adjusted independently in two directions at right angles to one another and comprising an element supported to move in a direction transverse to the axis of rotation of the motor, means for securing said element in its adjusted position, a sub-base carried by said element and extending in a direction substantially at right angles to the said direction of movement, said sub-base carrying a motor base support, and means comprising a rack carried by one of said parts and a pinion carried by the other, for adjusting said motor base support in a direction parallel to the axis of rotation of the motor, with respect to said sub-base and means for locking it automatically at any one of a number of predetermined positions.

7. A motor support whereby a motor may be supported and adjusted independently in two 75

- directions at right angles to one another and comprising an element supported to move in a direction transverse to the axis of rotation of the motor, means for securing said element in its 5 adjusted position, a sub-base carried by said element and extending in a direction substantially at right angles to the said direction of movement, said sub-base carrying a motor base support, and means comprising a rack carried by one of said 10 parts and a pinion carried by the other, for adjusting said motor base support in a direction parallel to the axis of rotation of the motor, with respect to said sub-base, and means including a notched segment and latch mechanism cooperating 15 with said segment whereby one of said parts may be adjusted to a number of definite predetermined positions with respect to the other and releasably retained in any such position.
8. A motor support whereby a motor may be 20 supported and adjusted independently in two directions at right angles to one another and comprising an element supported to move in a direction transverse to the axis of rotation of the motor, means for securing said element in its 25 adjusted position, a sub-base carried by said element and extending in a direction substantially at right angles to the said direction of movement, a motor base support carried by said sub-base, means comprising a rack and pinion 30 for adjusting said motor base support in a direction parallel to the axis of rotation of the motor, along said sub-base, said pinion having an operating member attached thereto, and means for latching said operating member at a number of 35 predetermined positions.
9. A motor support whereby a motor may be supported and adjusted independently in two directions at right angles to one another and

comprising an element supported to move in a direction transverse to the axis of rotation of the motor, means for securing said element in its adjusted position, a sub-base carried by said element and extending in a direction substantially at right angles to the said direction of movement, a motor base support carried by said sub-base, and means for adjusting said motor base support in a direction parallel to the axis of rotation of the motor, along said sub-base, said 5 means comprising a shaft having a screw thread thereon and also having a longitudinal groove, a latch cooperating with said groove and engaging therein once every revolution, said screw being threadedly engaged with one of said members and bearing against an abutment carried by the other to provide a number of definite latched steps of adjustment of one such member with respect to the other.

10. A motor support whereby a motor may be 20 supported and adjusted independently in two directions at right angles to one another and comprising an element supported to move in a direction transverse to the axis of rotation of the motor, means for securing said element in its 25 adjusted position, and a sub-base carried by said element and extending in a direction substantially at right angles to the said direction of movement, a motor base support carried by said sub-base, said sub-base having latch-receiving 30 notches formed in a side edge thereof and the motor base support having a spring-actuated latch member adapted to cooperate with said notches and having also a handle for moving such motor base support with respect to the sub- 35 base.

HERBERT E. TAUTZ.
